UNITED STATES PATENT OFFICE.

LEE C. SHARP, OF PLATTSMOUTH, NEBRASKA, ASSIGNOR TO AMERICAN CAN COMPANY, OF NEW YORK, N. Y., A CORPORATION OF NEW JERSEY.

MACHINE FOR FLANGING THE ENDS OF CAN-BODIES.

1,118,590.

Specification of Letters Patent.

Patented Nov. 24, 1914.

Application filed October 3, 1908. Serial No. 455,950.

To all whom it may concern:

Be it known that I, LEE C. SHARP, of 5
Plattsmouth, county of Cass, State of Nebraska, have invented certain new and useful Improvements in Machines for Flanging the Ends of Can-Bodies, of which the following is a full, clear, and exact specification, such as will enable others skilled in the art to which it appertains to make and 10 use the same.

My invention relates to a machine adapted to form flanges on the ends of can bodies fitting such bodies for the reception of the head of the can and the formation of a 15 crimped seam joining the head to the body. The device may be used in various connections either as a separate machine or as a part of an organized can body forming machine and when in this latter arrangement it serves to receive the bodies directly 20 from the body former and produce the flanges at a rate of speed corresponding to the speed of the body former. The construction of the end flanging mechanism is 25 such that a high speed of operation may be maintained. I also so organize the device that it serves as a self feeder taking the can bodies automatically from a chute or other receptacle provided therefor.

30 My invention involves various other features of importance all of which will be fully set forth hereinafter and particularly pointed out in the claims.

Reference is had to the accompanying 35 drawings which illustrate, as an example, one manner of embodying my invention, in which drawings,

Figure 1 is a front elevation of the device with parts in section; Fig. 2 is a sectional side elevation of the same with parts in 40 section; Fig. 3 is an enlarged longitudinal section taken completely through the flange forming parts. Fig. 4 is a detail view of one of the cams for reciprocating the flanging dies.

When the device is organized with a can 45 body former it is applied directly to the discharge chute thereof and when separately operated it is preferable to juxtapose the device to a chute in which the can bodies are placed and by which chute they are held in a superimposed pile ready to be passed successively through the flanging device. In 50 Figs. 1 and 2 the frame structure 10 may be taken to be either a part of the frame of a

body former or merely a support provided for the end flanging device and in this frame part 10 is arranged a chute 11 open at its upper end to receive the can bodies which are indicated at *a* in the drawings and having its lower end slightly curved toward the side of the frame part 10 to deliver the bodies properly to the flanging device. On said frame part 10 are mounted, preferably in horizontal alinement two boxes 12 in 60 which are arranged revoluble and slideable shafts 14. These shafts are pressed outward by coiled springs 15 thrusting against the outer ends of the boxes and against collars 16 secured to the outer ends of the 65 shafts. Said shafts 14 have their inner or adjacent ends spaced from each other to permit the passage of the can body between them and carry at their ends rotary heads 17 with inwardly projecting annular flanges 70 75 18 adapted to embrace the ends of the can bodies. Said heads 17 also are furnished with inwardly projecting arc-shaped stops 19 preferably constructed as continuations of the flanges 18 but of increased thickness 80 equal to the width of the flange formed on the can body so that said stop lugs 19 will engage the side surfaces of the can body and hold the can body properly positioned 85 for the operation of the flanging dies as indicated in Fig. 3.

The heads 17 are adapted to be rotated by any desired means but preferably through sprockets 20 secured to the heads and engaged by suitably driven chains 20^a. The 90 heads 17 have mounted on their outer surfaces rollers 21 adapted to engage short cams 22 on the adjacent or inner surfaces of the boxes 12, whereby upon the rotation of the heads 17, as the rollers 21 strike the 95 cams 22 said heads are momentarily moved inward toward each other and as the rollers disengage the cams the springs 15 instantly return the heads to separated position in which the rollers 21 run along the plane 100 inner surfaces of the bearings 12.

Carried by the heads and operating within the flanges 18 thereof are flanging dies 23. These are annular in form for a round can body and for angular can bodies may be given a corresponding angular shape. Each die is formed with a curved surface 23^a adapted to engage the edge of the can and by the curvature of such surface to spread out the end of the can in the form of a 110

flange as illustrated in Fig. 3. The dies 23 are fastened to studs 24 which are loosely arranged in longitudinal cavities 25 formed in the shafts 14 and said shafts are engaged by expansive springs 26 which tend to force the dies inward toward each other slightly in advance of the heads 17.

27 indicates pins carried in the shafts 14 and extending loosely through slots in the studs 24 limiting the motion of the studs in respect to the heads 17 and causing said studs and the dies carried thereby to be retracted with the heads for admission and discharge of the can bodies. It will be understood that the reciprocating movement imparted to the heads by the cams 22 is sufficient to separate the heads 17, 17, and also the dies 23, 23 sufficiently to permit the discharge and receiving of the can bodies, while at the same time permitting a limited movement of the dies 23 and studs 24 in respect to the heads 17.

In the operation of the device the heads 17 rotate continuously and in unison and the arc shaped stops 19 move past the end of the chute between the bottommost can and the one next above it. At this time the heads are moved to their outermost position and the can is free to fall into the space between the heads past the flanges 18, the can being at this time held by the stops 19 in proper position relatively to the dies 23. Instantly thereafter the rollers 21 strike the cams 22 and move the heads inward. When the heads are separated or moved outward the pile of cans is sustained in the chute 11 by the stops 19 and when the heads are moved inward the pile of cans is sustained by the flanges 18 as shown in Fig. 3. Instantly upon the inward motion of the heads the inclined surfaces 23^a engage the ends of the can body and force the same outward forming the flanges as shown in Fig. 3. It will be seen that the inward motion of the heads 17 causes the dies to move inward correspondingly while the springs 26 exert a steady pressure on the dies and cause them to engage the ends of the can body gradually. The inward motion of the dies and of the heads is of comparatively short duration the motion being practically an instantaneous inward and returned outward motion. This takes place without interrupting the rotation of the heads. As the stops 19 again move upward the heads separate, the can just operated on falls from the dies and is discharged from the machine and a new can is entered into engagement with the heads and dies as before explained. It will, therefore, be seen that this device is capable of a very high speed of operation, the heads rotating rapidly and a flanging operation being performed on both ends of the can once during each rotation.

65 The annular flanges 18 on the heads 17

serve as limiting walls to limit and true the flanges on the opposite ends of the can body as they are formed by the reciprocating dies 23, the flanges 18 thus serving as a portion of the dies in the formation of the flanges. 70 The shoulders formed by the semi-cylindric or arc shaped extensions 19 of the annular flanges 18 serve by engagement with the flanges on the can body as strippers to free the flanged can body from either die in case 75 the can body should tend to stick at one end in one of the dies.

Having thus described my invention, what I claim as new and desire to secure by Letters Patent of the United States is: 80

1. A mechanism for flanging the ends of can bodies, comprising a rotating die conforming in shape to and adapted to fit within the end of the can body and simultaneously engage the same at all points of its circumference and acting to turn a continuous flange on the can body around its entire circumference at the same time, an annular flange surrounding said die and adapted to be engaged by the flange on the can body 90 when formed, and automatically operated means for imparting to the die a back and forth motion longitudinally of the can body to spread outward and flange the end thereof, substantially as specified. 95

2. A mechanism for flanging the ends of can bodies, comprising a rotating head, a die concentric with and carried by said head and conforming in shape to and adapted to fit within the end of the can body, an annular flange surrounding said die, and automatically operated means for imparting to the die a back and forth motion axially of the can to spread outward and flange the end thereof, substantially as specified. 100

3. A mechanism for flanging the ends of can bodies comprising a rotating head, a die carried thereby and movable axially with respect thereto, means for moving the head and die axially of the can body whereby the die spreads outward or flanges the end thereof and means for yieldingly pressing the die in an axial direction independently of the head. 110

4. A mechanism for flanging the ends of can bodies comprising a rotating head, a die carried thereby and movable axially independently of the head and conforming in shape to and adapted to fit within the end of the can body, a cam adapted to move the head and die axially, whereby the die spreads outward or flanges the end of the can, means for yieldingly compressing the head against the cam and means for yieldingly pressing the die in an axial direction 115 120 125 independently of the head.

5. A mechanism for flanging the ends of can bodies comprising a bearing and cam thereon, a shaft mounted in the bearing to rotate and to move axially, a head carried 130

- by the shaft and adapted to be actuated by the cam, a spring pressing the shaft and head to hold the latter against the cam, a die carried by the head and movable independently thereof and means for pressing the die in an axial direction independently of the axial motion of the head. 5
6. A mechanism for flanging the ends of can bodies comprising a bearing, a cam thereon, a shaft mounted in the bearing to rotate and move axially, a head carried by the shaft and adapted to be actuated axially of the shaft by the cam, means for rotating the head and shaft, means for yieldingly 10 pressing the head toward the cam, a die, a stud thereon fitted loosely in a recess in the shaft, the stud and die turning with the head and shaft and means for yieldingly pressing the die and stud in an axial direction independently of the axial motion of the head. 15
7. A mechanism for flanging the ends of can bodies comprising a rotating head to engage the end of the can body, a die carried thereby and conforming in shape to and adapted to fit within the end of the can body and means for imparting to the die a back and forth motion axially of the can, whereby to spread outward or flange the end 20 thereof, said head having an annular flange to inclose the end of the can body. 25
8. A mechanism for flanging the ends of can bodies comprising a rotating head to engage the end of the can body, a die carried thereby and conforming in shape to and adapted to fit within the end of the can body, means for imparting to the die a back and forth motion axially of the can, whereby to spread outward or flange the end 30 thereof, said head having an annular flange to inclose the end of the can body. 35
9. A mechanism for flanging the ends of can bodies comprising a rotating head to engage the end of the can body, a die carried thereby and conforming in shape to and adapted to fit within the end of the can body automatically, operated means for imparting to the die a back and forth motion axially of the can, whereby to spread outward or flange the end thereof, and means on the head to hold and position the can body with respect to the die. 45
10. A mechanism for flanging the ends of can bodies comprising a rotating die to engage the end of the can, automatically operated means for imparting to the die a back and forth motion longitudinally of the can, whereby to spread outward or flange the end thereof and means to hold the can positioned for the action of the die, said die 50 engaging the end of the can body simultaneously at all points of its circumference and acting to form a continuous flange thereon at all points of the circumference of the can body at the same time, substantially as specified. 55
11. A mechanism for flanging the ends of can bodies, comprising rotating means to feed and hold the can body in position, and a tapering die concentric with said feeding and holding means and carried thereby and conforming in shape to and adapted to enter within the end of the can body and engage the same simultaneously at all points of its circumference and acting to form a continuous flange thereon at all points of its circumference at the same time, substantially as specified. 60
12. A mechanism for flanging the ends of can bodies, comprising a rotating means to feed and hold the can body in position, said rotating means comprising a head having a flange conforming to the cross sectional form of the can, but larger than the diameter thereof, and a tapering die within the flange adapted to enter the end of the can body and bend or draw the same outward 65 toward the said flange on the head. 70
13. In a mechanism for flanging the ends of can bodies comprising opposing rotating and reciprocating heads adapted to receive the can body between them and having flanges conforming to the cross sectional form of the can, but larger than the diameter thereof, said flanges receiving the ends of the can body, are shaped studs projecting inward from the flanges and adapted to position the can body and dies carried by the heads and adapted to enter the ends of the can bodies to draw or bend the same outward toward the flanges. 75
14. A machine for flanging can bodies, having means to rotate the can around its longitudinal axis and a reciprocating die adapted to engage the end of the can body during the rotation thereof to swage or bend said end and form a flange, said die fitting within the end of the can body and simultaneously engaging its entire circumference and acting to form a continuous flange around the whole circumference of the can body at the same time by the movement of the die in the direction of the axis of the can. 80
15. A machine for flanging the ends of can bodies, having means for rotating the can body around its longitudinal axis, a rotating die adapted to turn with the can and means for periodically reciprocating the die against the end of the can to swage or bend a flange thereon, said die fitting within the end of the can body and simultaneously engaging its entire circumference and acting to form a continuous flange around the whole circumference of the can body at the same time by the movement of the die in the direction of the axis of the can. 85

16. A means for flanging the ends of can bodies comprising a die adapted to engage the end of the body and swage or bend a flange thereon, and a limiting wall coacting with the die to limit and true the flange, said die fitting within the end of the can body and simultaneously engaging its entire circumference and acting to form a continuous flange around the whole circumference of the can body at the same time by the movement of the die in the direction of the axis of the can.

17. A means for forming flanges on can bodies having a die adapted to enter the end of the can and spread or swage outward a flange thereon, said die fitting within the end of the can body and simultaneously engaging its entire circumference and acting to form a continuous flange around the whole circumference of the can body at the same time by the movement of the die in the direction of the axis of the can and a limiting wall coacting with the die inclosing said flange to true the same, and means for forcing the die and can body together in the direction of the length of the can body.

18. A means for forming flanges on can bodies comprising a die adapted to enter the end of the can and swage or bend a flange outward thereon, said die fitting within the end of the can body and simultaneously engaging its entire circumference and acting to form a continuous flange around the whole circumference of the can body at the same time by the movement of the die in the direction of the axis of the can, said die having an outwardly projecting lip or flange against which the flange of the can is formed and means for forcing the die and can body together in the direction of the length of the can body.

19. A means for forming flanges on can bodies comprising a die adapted to enter the end of the can and swage or bend a flange outward thereon, said die fitting within the end of the can body and simultaneously engaging its entire circumference and acting to form a continuous flange around the whole circumference of the can body at the same time by the movement of the die in the direction of the axis of the can, said die having an outwardly projecting lip or flange against which the flange of the can is formed, and a limiting wall surrounding said lip or flange and serving to limit and true the flange on the can and means for forcing the die and can body together in the direction of the length of the can body.

20. A machine for forming flanges on can bodies, having a rotating and reciprocating die adapted to engage the end of the can to form the flange and a limiting wall rotating with the die to engage the edge of the flange and limit and true the same, said die fitting

within the end of the can body and simultaneously engaging its entire circumference and acting to form a continuous flange around the whole circumference of the can body at the same time, and means for delivering and supporting the can body axially in line with said die.

21. A machine for forming flanges on can bodies comprising a rotating and reciprocating die to form the flange and a rotating means for positioning the can to the die.

22. A means for forming flanges on can bodies, having a reciprocating die to form a flange, a limiting wall for the flange to abut against, and a stripper acting in unison therewith to disengage the can from the die, said die fitting within the end of the can body and simultaneously engaging its entire circumference and acting to form a continuous flange around the whole circumference of the can body at the same time, and means for delivering and supporting the can body axially in line with said die.

23. A means for forming flanges on can bodies comprising opposing dies to engage the ends of the can body, limiting walls for the flanges to abut against, and strippers moving in unison with the dies to disengage the can from the die or dies, each of said dies fitting within the end of the can body and simultaneously engaging its entire circumference and acting to form a continuous flange around the whole circumference of the can body at the same time, and means for delivering and supporting one by one the can bodies between said dies.

24. A means for forming outward flanges on the ends of can bodies, comprising opposing dies to form flanges, and coacting means surrounding the dies to limit the flanges and to engage the formed flanges to separate the can from the dies.

25. A means for flanging can bodies, having a die and a wall juxtaposed thereto to position the can body to a die, such wall having a flange to engage the flange of the can for the purpose specified.

26. A means for flanging can bodies, having a former head with a limiting flange thereon, a die inclosed by said flange and a means carried by the former head to position the can to the die.

27. A means for forming flanges on can bodies, having a former head, a limiting flange thereon and a die inclosed by the flange, said flange being extended at one point to form a wall and the wall having an inward flange for the purpose specified.

28. A machine for operating on the ends of can bodies, having a rotating and reciprocating die and a wall surrounding and rotating with the same, the wall serving to position the can to the die and to limit the extent of the flange formed by the forcing of the die and can body together, said die

- fitting within the end of the can body and simultaneously engaging its entire circumference and acting to form a continuous flange around the whole circumference of the can body at the same time. 5
29. In a machine for performing operations on the ends of can bodies, the combination of a chute to hold a number of can bodies, a rotating tool or die to act on the can body and a wall projecting beyond the tool or die and rotating therewith past the end of the chute, the wall serving successively to enter the can bodies into position opposite the tool and to hold back the other can bodies during the operation of the tool. 10
30. In a machine for performing operations on the ends of can bodies, the combination of a chute to carry the can bodies, a tool or die to act thereon and a wall moving in a rotary course past the mouth of the chute and serving successively to receive the can bodies and position them to the tool or die, said wall also serving to hold the remaining can bodies during the action of the tool or die, said die fitting within the end of the can body and simultaneously engaging its entire circumference and acting to form a continuous flange around the whole circumference of the can body at the same time by the movement of the die in the direction of the axis of the can. 15
31. In a machine for performing operations on the ends of can bodies, the combination of a chute, two opposing tools or dies arranged at the mouth of the chute and a rotating wall moving past the mouth of the chute and serving successively to position the can bodies to the tools or dies and to hold back in the chute the remaining can bodies during the operation of the tools or dies. 20
32. In a machine for making cans, the combination of a flanging die having a surrounding limiting wall for the flange to abut against, a rotatable and reciprocal spindle carrying the same, means for rotating the spindle including a cam serving periodically to move the shaft axially in one direction and means to return the shaft. 25
33. In a machine for making cans, the combination of a flanging die having a surrounding limiting wall for the flange to abut against, a revolute and reciprocal shaft on which the same is carried, a means for rotating said shaft, a spring pressing the shaft in one direction and means including a cam periodically to move the shaft contrary to the spring, said die fitting within the end of the can body and simultaneously engaging its entire circumference and acting to form a continuous flange around the whole circumference of the can body at the same time by the movement of the die in the direction of the axis of the can. 30
34. In a machine for making cans, the combination of a flanging die having a sur- 65
- rounding limiting wall for the flange to abut against, a revolute and reciprocal shaft to carry the same, means to rotate the shaft, a spring to press the shaft axially in one direction, a roller attached to the shaft to move with it, and a track disk engaged by the roller and having a cam thereon periodically to move the shaft contrary to the spring, said die fitting within the end of the can body and simultaneously engaging its entire circumference and acting to form a continuous flange around the whole circumference of the can body at the same time by the movement of the die in the direction of the axis of the can. 70
35. The combination with a pair of opposing flanging dies having surrounding limiting walls for the flanges to abut against, of means for supporting a can body in position between said dies and means for forcing said dies toward each other and separating the same, each of said dies fitting within the end of the can body and simultaneously engaging its entire circumference and acting to form a continuous flange around the whole circumference of the can body at the same time, substantially as specified. 75
36. A flanging head including in combination, a stem, a cap carried thereby, a limiting ring seated on said cap, a die located within said ring and having its curved forming face within the outer edges of the limiting ring when the head is pressed against the metal, whereby the edge of the metal being bent by the forming die, is brought into engagement with the limiting ring. 80
37. A flanging head including in combination, a stem, a cap carried thereby, a limiting ring seated on said cap, a die located within said ring and having its curved forming face within the outer edges of the limiting ring when the head is pressed against the metal, whereby the edge of the metal being bent by the forming die is brought into engagement with the limiting ring, and means whereby said die is yieldingly moved relative to the flanging head to strip the metal from the flanging head. 85
38. In a can flanging machine, means for loosely holding a can body, a flanging die adapted to engage circumferentially the end of the can body, and turn the same outwardly to form a projecting flange thereon, and having a stop shoulder adapted to be encountered by the edge of the sheet metal and thereby limit the projection of the flange, combined with means for pressing said die and the can body together by pressure exerted through the can body in a direction longitudinally of the body, whereby the entire circumference of the end of the body is simultaneously turned outwardly to form the flange which is terminated by said shoulder. 90
39. In a can flanging machine, a pair of 95

flanging dies adapted to engage the opposite ends of a can body, each die adapted to engage circumferentially one end of the can body and having a centering projection adapted to enter the can body, with an outwardly flaring shoulder at the base thereof, and an annular stop shoulder surrounding the same, adapted to limit the projection of the flange, combined with means for forcing said dies together against a can body held between them, whereby the entire cir-

cumference of each end of the can body is simultaneously turned outwardly to form the flange which is terminated by said shoulder.

Corrections in Letters Patent No. 1,118,590.

It is hereby certified that in Letters Patent No. 1,118,590, granted November 24, 1914, upon the application of Lee C. Sharp, of Plattsmouth, Nebraska, for an improvement in "Machines for Flanging the Ends of Can-Bodies," errors appear in the printed specification requiring correction as follows: Page 3, line 50, after the word "body" insert a comma, and same line, after the word "automatically" strike out the comma; page 4, line 23, after the word "die" insert the word *and*; and that the said Letters Patent should be read with these corrections therein that the same may conform to the record of the case in the Patent Office.

Signed and sealed this 26th day of January, A. D., 1915.

[SEAL.]

R. F. WHITEHEAD,

Acting Commissioner of Patents.
